(57) **CLAIM**

The ornamental design for an aeration tine for a lawn tending machine, as shown and described.

DESCRIPTION

FIG. 1 is a perspective view of an aeration tine for a lawn tending machine;

FIG. 2 is a front elevational view thereof;

FIG. 3 is a right side elevational view thereof;

FIG. 4 is a rear elevational view thereof;

FIG. 5 is an enlarged top plan view thereof; and,

FIG. 6 is an enlarged bottom plan view thereof.

1 Claim, 2 Drawing Sheets

FIG. 2

FIG. 1

FIG. 5

FIG. 6

FIG. 4

FIG. 3
